UNITED STATES PATENT OFFICE.

BERNARD F. WEBER AND FRANK E. WOODFORD, OF CHICAGO, ILLINOIS; SAID
WOODFORD ASSIGNOR, BY MESNE ASSIGNMENTS, TO RAYMOND C. PENFIELD,
OF NEW YORK, N. Y.

CONVEYER SYSTEM.

1,402,558.

Specified of Letters Patent. Patented Jan. 3, 1922.

Application filed August 21, 1912. Serial No. 716,318.

To all whom it may concern:

Be it known that we, BERNARD F. WEBER and FRANK E. WOODFORD, citizens of the United States, and residents of Chicago, in the State of Illinois, have invented certain new and useful Improvements in Conveyer Systems, of which the following is a specification.

Our present invention relates to conveyers 10 in general and more particularly aerial tramways, and has special reference to the intramural transportation of articles in process of manufacture from one part of the manufacturing establishment to another part 15 thereof. In the present instance, we have shown an embodiment of our invention especially adapted for use in making, loading and unloading bricks in a brick yard, other parts of such system forming the subjects 20 matter of our co-pending applications Serial No. 545,616 filed February 24, 1910, and Serial No. 576,172, filed August 8, 1910, a division thereof, and in which applications the subject matter of this present application 25 is disclosed.

The principal objects of our present invention are: the provision of automatically operated carrier apparatus for transferring brick, as they issue from the brick making 30 machine, to the cars upon which they are "hacked" preparatory to storing, drying or burning, with the intervention of a minimum amount of manual labor; the provision of an improved form of mono-rail tracks for 35 supporting the conveyer units and elevating or lowering them to any desired level for convenience in taking up and depositing the load; the provision of an improved design of motor driven trolley car for operating 40 the individual carriers; the provision of an improved form of individual carriers for supporting the goods to be transported; the provision of co-operating means whereby 45 the operation of the carrier units, and of the engaging means carried thereby, may be varied when desired and thereafter automatically restored; the provision of improved means for intermittently driving the individual conveyer units; the provision of 50 improved means for intermittently energizing the engaging mechanism and causing them to engage the articles to be transported; the provision of automatically operated electrical means for controlling the 55 movements of each of the individual trolley

cars and of the engaging means carried thereby; together with such other objects as may hereinafter appear.

In the manufacture of bricks as customarily carried on at this day, the bricks as 60 they issue from the forming mechanism are deposited upon an endless belt conveyer running to a point adjacent to a series of cars, and as the bricks approach the cars they are manually lifted from the belt and placed in 65 the desired position upon the cars. This system of operation is objectionable in the following respects:

Firstly. In order that it may be carried out at all, all of the operatives removing 70 bricks from the conveyer and the belt and hacking them on the cars, must move in unison to avoid interference, and the speed with which the transference of the brick may be accomplished is governed by that of the 75 least efficient operator;

Secondly. Much time is lost and the capacity of the plant reduced in the event of the absence for any cause of one of the operatives; that is, any variation in the number 80 of operatives, even for a short time, requires the proportionate variation in the speed of the conveyer belt;

Thirdly. In the event that the operatives become incoordinated even momentarily, 85 some of the bricks must pass by and become lost;

Fourthly. For the efficient disposition of the brick issuing from but a single forming mechanism, the employment of a large number 90 of operatives is required;

In attaining the objects above mentioned and gaining certain further benefits and advantages below to be described, we have provided a construction one embodiment of 95 which is illustrated in the accompanying drawings wherein—

Figure 1 is a general schematic view of a conveyer system embodying our improvements as useful in a brick making establishment;

Figure 2 is an enlarged transverse elevational view, partially in section, taken on the line II—II of Figure 1 the dotted lines indicating the various aerial track levels at 105 different heights above the ground tracks;

Figure 3 is a diagrammatic view illustrative of the relative positions assumed by the several members of a series of trolley car units and carrier units as they respectively 110

come into position to engage, and complete the operation or engagement of, the several members of a row of brick.

Figure 3^a shows a part of the machine of Figure 3, being a continuation of the right hand end thereof;

Figure 4 is a view of a detail of construction; and Figure 5 is a diagrammatic view showing the circuits for the motor and the solenoid.

Referring first to Figure 1 or the drawings, it will be observed that we have here illustrated the following principal elements, in connection with a brick making machine 15 viz.: an aerial trolley car track, A, A, A, located immediately above a conveyer belt B adapted to receive brick as they come from the forming machine; a plurality of motor trolley cars C running on the track A; carrier devices D respectively supported by the trolley cars C; a plurality of branch tracks E, E', E², etc., diverging from the main track A and afterwards converging therewith, each of said tracks E, E', E², etc., 20 being provided with a switch F, F', F², etc., and switch operating means G, G', G², etc., a single circuit changer H for completing in rotation the circuits through the several actuating means G; a plurality of flat cars 30 J on ground tracks K, upon which cars the bricks may be packed preparatory to storing, drying or burning, the ground tracks being disposed transversely to the trolley car tracks E, E', E², etc., driving mechanism M 35 for imparting a continuous motion to the flat cars J as they traverse the planes of the aerial tracks E, E', E², etc., self-closing switches N arranged to normally connect the branch tracks E, E', E², etc., with that part 40 of the main track A indicated at P; a suitable electrical conductor Q for feeding the trolley car motors, and a suitable conductor R for energizing the operating means actuating the engaging devices of the carriers 45 D; secondary conductors S located adjacent the branches T of the conductor Q; short branches V of the conductor R; secondary conductors X located adjacent that part of the conductor Q indicated at Y, and circuit changers Z for controlling the feed to 50 the conductors S and X, it being understood that a common return for all electrical equipment is had through the rail A to the ground W.

Referring now more particularly to Figures 1 and 2, it will be observed that the center branches E, E', E² and E³ of the main aerial trolley car track A are located above the ground rails K upon which the flat cars 60 J move. In practice each aerial track is used for depositing a different layer of bricks on the flat cars. By thus providing a separate trolley car track at a different height for depositing each layer of bricks on the car J, the carriers D will at all times be con-

veniently close to the surface of the flat cars J or to the bricks piled thereupon, thereby avoiding not only unnecessary expenditure of effort by the operatives in discharging the bricks upon the car, but also danger of breakage of such bricks by dropping them. In order that each of the flat cars J may be moved from a convenient position below the track E³ to the track E², E' and E, in succession, at a rate of speed which will approximate the rate of delivery of brick by the carriers D, we preferably utilize the driving mechanism indicated at M in Figure 1, wherein as will be seen upon reference to Figure 2, the conveyer M (driven by a motor 10) is of a chain construction and provided with arms 11 normally disposed at right angles to the conveyer, and movable relatively thereto in one direction only, to-wit: the direction of normal travel of the conveyer, such arms 11 being adapted to engage the axles 12 of the cars J and drive such cars forward in the direction indicated by the arrow.

For driving the motor of the trolley car C, 90 and energizing the actuating means for the engaging mechanism D, we make use preferably of two conductors, Q and R respectively, having a common feed of the same polarity, such conductors being supported from a suitable bracket but insulated therefrom and spaced somewhat apart, as indicated at 95 13, contact being made with the conductors Q and R respectively by the collector shoes 14 and 15, of the motor of the trolley car C and 100 of the actuating device 16 of the carrier D, respectively, which shoes are, of course, insulated from each other.

In that embodiment of our invention 105 which is specially available for use in connection with an "end out" brick machine (that is one which forms the brick from a bar of the two least dimensions of a completed brick) we make use of a construction of carrier and engaging mechanism illustrated in preferred form in Figure 3.

Referring now more particularly to Figure 3, which illustrates more fully the construction of the trolley car indicated at C in Figure 1, it will be observed that the present 115 form of trolley car comprises a frame 17 having a pair of supporting wheels 18-18, riding upon the aerial track A which is supported from a bracket. The frame 17 is provided at each end with upturned bumpers 19 rounded for a purpose to be below described, and upon one end of the frame is mounted a motor 20 in turn mounted to drive one of the trolley car wheels 18. For the purpose of affording a pivotal support for the carriers 120 D of Figure 1, we mount centrally in the lower part 21 of the frame 17, pivotally, a hanging bar 22 for the carrier device D. The central longitudinal member 23 of the carrier D is provided with suitable attaching 125

posts 24 by means of which it may be suspended by flexible means (here indicated as a pair of chains 25) from the trolley C.

The rear end of the carrier D is provided 5 with an upstanding stop 26 bifurcated as indicated at 27 in order to provide a socket for the projecting end 28 of the following carrier, and the forward end with a downwardly extending stop plate 29 both useful for purposes to be below described.

Referring further to Figure 3, it will be observed that we have here shown a plurality of the trolley cars C and carriers D in the positions they assume relatively to each other 15 and the brick 30 as such brick are discharged upon the belt B upon emergence from the brick forming device 31, at the time the conveyer units ride into position to engage such brick.

20 We have indicated a brick forming machine at 31 purely for purposes of illustration, here showing the well known Chambers machine wherein the molded clay as it issues from the die a of the mixing machine b is delivered to an off-bearing belt c which moves at a rate of speed substantially uniform with that of the molded material coming from the die and delivers such material to a cutting machine d having arms e provided with cutter wires f for cutting the molded clay into 25 bricks 30. In order that the bricks 30 may not be distorted by crowding or otherwise deformed, they are delivered immediately upon cutting from the off-bearing belt c to the belt B which being arranged to travel at a higher rate of speed than the belt c acts as a separator, thereby carrying the bricks 30 forward in the spaced relation shown. The members a, b, c, d, e, f, and B comprise an 30 arrangement well known to those who are skilled in the art, and the belt B is always driven in such arrangements at a rate of speed in excess of the maximum speed of the belt c, which may be done by driving the belt 35 B from the pulley which drives the belt c in the customary manner.

From an examination of this Figure 3 it will be observed that a portion 32^a of the track A, nearest the point of emergence of 50 the brick from the device 31 upon the belt B, is elevated a distance equal substantially to the thickness of the brick, above that portion of the track indicated at 33 where the carriers D engage the brick, and that 55 the rounded bumpers 19 are provided for the purpose of spacing the trolley cars C apart a distance slightly less than the length of the carriers D to allow overlapping of the latter. When each of the trolley cars C 60 moves off the elevated portion of the track C the projecting portion 28 of the clamp will ride into the notched portions 27 of the forward clamp and prevent the rear clamp from any contact whatsoever with the brick 65 engaged or about to become engaged with

such forward carrier, as is very clearly to be seen on the comparison of the relative positions of the several carriers D', D^a and D^b. This construction also permits the use of the downwardly extending stop plate for 70 retarding the brick as is desirable in the operation of our device below to be described.

The operation of a brick transporting apparatus embodying our present invention is 75 as follows:

Assuming a plurality of carriers coming vertically over the belt B as is clearly to be understood from Figures 1 and 3. Immediately the collector shoe 14 passes out of contact with that part of the conductor Q indicated at 47, the trolley car C descends the inclined portion 33 of the aerial track A, allowing the elements 34, 35, and 36 to come into position to engage the brick 30 as may be seen at D', D^a and D^b. Conveyer 80 B will move at greater speed than the trolley car C' until the motor of the trolley car C' is energized, and the carrier D' will thereby and by the impact of the carrier D^a be moved to the position shown and its prior 85 positions successively occupied by D^a and D^b, but carrier D, since the motor of its trolley car C is still energized, continues to push against the line of carriers D', D^a, etc., and move said carriers one at a time 90 into transporting engagement with the groups of bricks, such as 30^a, 30^b, 30^c and 30^a, 30^b, 30^c. Obviously, however, notwithstanding the fact that the motor of the trolley car C' is energized, the line of carriers each provided with a retarding plate 95 29 will move at a slightly slower rate of speed than that of the belt B, owing to the inertia of such line, and the motor of one of the trolley cars C, will act as a carrier distributing mechanism operating in unison with the forward movement of the bricks for delivering one carrier at a time as fast as a load of bricks gets in proper position to be taken up by such carrier. As soon as 100 the collector shoe 14 strikes the guideway indicated at 37, the trolley car C' will be energized and the carrier D^a will assume the relation parallel to the belt like that shown for the carrier D'. As the motion of the 105 conveyer B in the direction indicated by the arrow is continuous, and the retarding plate 29 of the carrier D^a has dropped in front of the brick 30^a consequent upon the removal of the carrier D', the bricks 30^a, 30^b, and 110 30^c will close together similarly to those indicated at 30^a, 30^b, 30^c, the carrier D^a thereby acting as an automatic bunching mechanism cooperating in timed relation with the separating belt B. Immediately the collector shoe 115 15 strikes the guideway 38 of the conductor R the actuating device 16 will become energized, and the bricks finally clamped in the carrier and any curvature in their surfaces straightened. The brick 120 125 130

135

- clamped in the carrier still contacting with the conveyer B, the carrier continues to progress in the direction indicated by the arrow until the contact shoe 14 strikes that 5 part of the conductor Q indicated at 37 when the motor is energized and begins its travel along the track A, the speed of the motors of the carriers C, after they leave the separating belt B, being obviously much greater 10 than that of the separating belt B, which in turn is greater than that of the line of carriers, C, notwithstanding the push of the carrier C² whose motor is retarded by the overload caused by the weight and the frictional resistance of the line of carriers in 15 front of it.
- As the trolley car C' approaches the circuit changer H and strikes one of the fingers 39 (see Figure 1) closing the circuit through 20 the wire 40, the solenoid G (Figure 1) is excited, the switch F (Figure 1) is closed and the trolley car C' is diverted down the track E. The approach of the following trolley car C² will move another of the fingers 39 25 open the circuit through the solenoid G and open the switch F, simultaneously closing the circuit through the wire 41, the solenoid G' and closing the switch F', like operations taking place with respect to the switch F² of 30 the track E², and the switch F² of the track E³, opening the switch previously closed and closing the next one in order, etc. When the contact shoe 14 of the carriers C reaches the 35 point on the conductor T (forming substantially a continuation of the conductor Q) indicated at 43, the energization of the motor is discontinued and the trolley car comes to a stop, but the actuating device 16 continues to be energized. The operator 40 standing at O then grasps the carrier D with his hand and brings it to its desired position above the car J, pulls down the carrier by extending the springs 44, and opens the clamp and discharges the brick by pressing 45 upon the switch button 45, arranged in the rearward of the two members 24, which opens the circuit through the actuating device 16. The carrier D being relieved of the weight of the brick will immediately rise 50 from the brick by means of the springs 44 previously held under tension, and the carrier may be then given a manual impulse along the aerial track E, and as soon as the contact 14 strikes that part of the conductor 55 T indicated at 46, the motor 34 will become energized and the carrier will proceed on its way along the aerial track E and over the switch N and the aerial track A until the trolley car C again reaches the terminal 60 when the operation first described will be repeated.

From the foregoing description it will be apparent that to attain a most efficient operation of apparatus embodying our improvements, it is desirable that the brick be

somewhat spaced apart prior to the instant of their final engagement with the carriers D.

If for any reason delivery of brick to the flat cars be temporarily suspended, the trolley car C may be diverted to the storage track indicated at A^x having conductors R^x and Q^x, and communicating with the track A by means of a manually operated switch F^x and a spring switch E^x.

Having thus described our invention and illustrated its use what we claim as new and desire to secure by Letters Patent is:

1. In an apparatus of the kind described, means for delivering successive groups of 80 bricks in position for transportation, and moving carrier means for receiving said moving bricks and delivering said bricks to a hacking stand in hacked relation.

2. In an apparatus of the kind described, 85 automatic means to bunch together bricks in the desired units required for hacking, and automatic carrying mechanism for carrying said bunched-together units and depositing them in hacked relation.

3. In an apparatus of the kind described, 90 mechanism for continuously delivering a stream of bricks, mechanism for carrying said bricks forward in successive bunches to a hacking station, and means for introducing a time element between the deliveries of bunches, without interrupting the aforesaid continuous movement of the bricks, for permitting the proper handling of the 95 bricks at the hacking station.

4. In an apparatus of the kind described, the combination with mechanism for continuously delivering a stream of green brick-material in the form of bricks, and carrying means for carrying said bricks to hacking 105 stations, of means for providing a time interval at the beginning of each carrying movement and means for providing another time interval at the end of each carrying movement for enabling the carrying 110 means to take its load of bricks and deposit its load in hacked relation without interfering with the said continuous movement of the stream of bricks.

5. In an apparatus of the kind described, 115 means for moving a stream of bricks forward into position for being loaded in units of a plurality of bricks each, carriers for carrying said bricks, and carrier distributing mechanism operated in unison with the 120 forward movement of the bricks for delivering one carrier at a time as fast as a load of bricks gets in proper position for said carrier.

6. In an apparatus of the kind described, 125 continuously moving brick-delivery means for delivering bricks with a continuous forward movement in position to be loaded, a carrier for transporting said bricks, means adjacent the loading portion of said deliv-

70

ery means for positively moving said carrier at the same speed as the bricks, and co-operating automatic mechanism for securing a load of bricks on said carrier while the carrier and bricks are still moving.

7. In an apparatus of the kind described, means for receiving a continuous stream of bricks, means for forwarding the same in separated bunches, hacking clamps and 10 means for delivering said bunches to said hacking clamps with a space interval between deliveries.

8. In an apparatus of the kind described, means for receiving a continuous stream of 15 bricks, means for segregating bunches of bricks from such stream, and for delivering

successive bunches to different stations for subsequent treatment.

9. In an apparatus of the kind described, means for receiving a continuous stream of 20 bricks, means for forwarding the same in separated bunches, and means for delivering successive bunches to separated stations.

In witness whereof we have hereunder signed our names in the presence of the two 25 subscribed witnesses.
